GUIDING AND LOCKING DEVICE FOR
WINDOW SASH

Cecil C. Stewart, Champaign, Ill.

Application July 14, 1939, Serial No. 284,402

11 Claims. (Cl. 292—160)

The present invention relates to guiding and locking devices for window sash, and is particularly concerned with such guiding and locking devices, and will enable the removal of the sash for cleaning, repair, or other purposes, and eliminate the necessity for the dangerous work outside of buildings on the ordinary window sash, such as exemplified by the prior art.

One of the objects of the invention is the provision of an improved removable, self-adjusting window sash, which is adapted to be removed or replaced with a minimum amount of work, and which enables the operator to take the sash out of the window frame at any time from the inside for cleaning or repair.

Another object of the invention is the provision of a window sash installation of the class described, which is self-locking on the closed position and at the ventilation position, and which cannot be unlocked or raised from the outside when it is in either of these positions.

Another object of the invention is the provision of an improved window sash and frame structure of the class described, which is adapted to compensate for the shrinking and swelling of the sash or frame, and which may be installed with or without weather strips.

Another object of the invention is the provision of an improved sash locking arrangement which lends itself to control of the ventilation by the janitor only or by some other authorized person so that it is impossible for other occupants to tamper with the ventilation when the sash has been set in any adjusted position.

Another object of the invention is the provision of a window sash installation which is non-rattling, sturdy, simple, adaptable to new sash or sash which has already been installed, and on storm sash and screens, and which may also be used on steel sash and in double hung style.

Another object of the invention is the provision of improved window sash installation and lock having special provision for a setting of all the locks in open position so that it will be unnecessary for a painter to come into the house to work when the sash are all set in this position.

Another object of the invention is the elimination of window stops allowing the more compact sash installation and providing space for blinds to be set inside the frame clear of the wall.

Another object is the provision of an improved guide and locking hardware for window sash, by means of which the sash weights, cords, and stops may be eliminated and the sash so installed that they may be secured in any desired position or completely removed from the frame at will.

Other objects and advantages of the invention will be apparent from the following description and the accompanying drawings, in which similar

characters of reference indicate similar parts throughout the several views.

Referring to the drawings:

Fig. 1 is an inside elevational view of a window frame equipped with sash installed according to the present invention;

Fig. 2 is a larger vertical sectional view, taken on the plane of the line 2—2 of Fig. 1, looking in the direction of the arrows;

Fig. 3 is a horizontal sectional view, taken on the plane of the line 3—3 of Fig. 1, looking in the direction of the arrows;

Fig. 4 is a fragmentary horizontal sectional view, taken on the plane of the line 4—4 of Fig. 1;

Fig. 5 is a fragmentary elevational view in partial section, showing details of structure of the movable guide support and locking arrangement;

Fig. 6 is a fragmentary horizontal sectional view, taken on the plane of the line 6—6 of Fig. 5, looking in the direction of the arrows;

Fig. 7 is a fragmentary vertical sectional view, taken on the plane of the line 7—7 of Fig. 5, looking in the direction of the arrows;

Fig. 8 is a fragmentary horizontal sectional view, similar to Fig. 6, with the parts in the position which they assume when the guide bar is pinned in the unlocked position;

Fig. 9 is a fragmentary horizontal sectional view, taken at the right side of the window frame and sash, showing a modified form of structure;

Fig. 10 is a vertical elevational view of the combined guide bar and locking bar;

Fig. 11 is a view in perspective of a special screw used for locking the sash in certain positions.

Referring to Figs. 1 to 3, 20 indicates in its entirety the window frame, which is provided with the upper sash, indicated by 21, and lower sash 22.

The sash may be of any conventional structure, and may be made of wood, metal, or may comprise storm sash or screens.

The frames of the sash 21 and 22 may be regarded as exemplary of the frames or supports of many different types of closures which may be slidably mounted and secured according to the present invention.

According to the present invention, the customary window stops may be completely eliminated and the sash pulleys and weights are eliminated, as the window sash hardware constructed according to the present invention contemplates the securement of the window in various positions by means of a guide bar, which may also serve as a lock.

The window frame 20 has its vertical side members 23 and 31, which engage the edges of the sash, provided with the grooves 24, 25, 26 and 27,

for slidably receiving suitable guide members carried by the sash, as shown in Fig. 3.

One side of each sash, preferably the left side, may be provided with a fixed guide member, such as, for example, the angle iron member 28, having one flange 29, mortised in the edge of the sash and secured therein by suitable wood screws passing through apertures in the flange 29, and the other flange 30 projecting in a plane parallel to the plane of the sash, and engaging in either the groove 26 or 27.

The groove 27 is for the lower sash, and the groove 26 for the fixed guide 28 of the upper sash.

If desired, both of the grooves 26, 27, as well as the grooves 24 and 25, may be provided with a metal lining, which also extends over the inner surface of the side frame members 23 and 31 of the window frame, giving a smooth metal surface for engaging the guide members and the edges of the sash and for producing a sealing effect similar to that of various types of weatherstripping.

Referring to Fig. 9, it will be observed that the grooves 24 and 25 of that modification have been lined with U-shaped sheet metal members 32 and 33, having laterally extending attaching flanges. The U-shaped lining member 33 must, of course, have apertures for receiving the locking screws, further to be described, in regard to Figs. 3 and other figures.

The other edge of each sash, preferably the right edge, is provided with a locking and guiding arrangement, which includes the combined locking and guiding bar 35 of Fig. 10. This locking bar may consist of a bar of steel or other sheet metal, suitably treated or galvanized to prevent corrosion, and extending the full length of each sash.

The right-hand edge of each sash is provided with a relatively deep groove 36 for receiving the full width of each bar 35, so that the bar may be recessed in the sash or withdrawn into the sash to remove the guide bar 35 from its groove 25 or 24. When the guide bar is so withdrawn into the sash, it will be evident that the suitable clearance between the sash and the frame and between the guide angle 28 and its groove 26 or 27 permits the sash to be pivoted inward on the guide 28 as a vertical pivot for removal from the frame.

Thus both of the sash may be removed from the inside for painting, cleaning, or other operations.

The guide bar 35 (Fig. 10) is provided with a multiplicity of grooves 40 to 50, the walls of which provide retaining shoulders for engagement with suitable keepers or stops located in the grooves 24 and 25. Any number of such grooves may be utilized, depending upon the number of positions in which it is desired to set the window sash, and the number shown is merely exemplary of one preferred type of construction.

The grooves 24 and 25 are provided with a plurality of stop screws of two types, 51 and 52. The stop screws 51 are exemplified in Fig. 5, and may consist of ordinary round headed wood screws made of suitable non-corrodible metal, and provided with the ordinary slot 53 for receiving a screw driver, and having one side 54 filed off flat, to provide a horizontal shoulder. These flat horizontal shoulders on the wood screws 51 all have the flat side upward when the screws are installed in the grooves 24 and 25, as shown in Fig. 2. Such screws, for example, in the groove 25, which receives the guide for the lower sash,

may be used at regularly spaced points of, for example 2½" each from the top of the window down to the two last stop screws, which are of the type of the screws 52.

5 The stop screws 52 are exemplified in Fig. 11, and may be square headed stop screws, having the flat sides 55 and 56 on the upper and lower sides of the stop screw heads when they are installed in the grooves 24 and 25.

10 It will be noted that in Fig. 2 the specially constructed round headed screws are utilized in the groove 24 at every point from the top of the window to the middle of the frame, except the two uppermost stop screws are of the type 52.

15 The square headed stop screws 52 are used wherever it is desired to effect a positive locking of the guide bar 35 against motion in either direction, and the rounded headed lock screws are used at other points where it is desired to permit the round side of the screw to cam the locking bar 35 inward when the window is lifted.

20 Referring again to Fig. 10, it will be noted that each of the grooves 40—50, inclusive, has an abrupt transverse shoulder 57 on the upper side, 25 but the lower corner is beveled off at 58 sufficiently to permit the guide bar to ride up over a round headed screw. The abrupt shoulders 57 will engage the flat shoulders 54 on the round headed screws 51 or the flat shoulders 55 on the square headed screws 52 and hold the window against downward movement.

25 The beveled camming surfaces 58 will ride over round headed screws and cause the bar 35 to be cammed into its slot 36 in the sash when the sash is raised, without using the key or other mechanism to withdraw the bar 35. However, the remaining abrupt shoulder 59 on the lower side of each of the slots 40 to 50, inclusive, is still adequate to cause a locking engagement between a square headed screw 52 and the locking bar 35 and to prevent upward movement of the locking bar whenever the locking bar engages a square headed screw.

30 The two square headed screws 52 utilized at the bottom of the groove 25 (Fig. 2) serve the purpose of permitting the locking of the lower sash either in the closed position or in the next position about 2½" higher, for example, which I shall call the ventilation position. The height 35 of this ventilation position is such that it does not permit the insertion of a hand, but still permits some ventilation.

35 The two square headed screws used at the top of the groove 24 (Fig. 2) may be used to lock the upper sash in its closed position or to lock it in a "ventilation" position a predetermined distance below the upper border of the frame.

40 The sash is preferably provided with means for resiliently urging the locking and guiding bar 35 outward into the grooves 24 or 25. This resilient means may take the form of a pair of spring units 60, one at the lower part of each locking bar, and one adjacent the upper end. These spring units may be identical, and each may consist of a tubular metal member 61, having a through bore, which is threaded internally at 62 and provided with a slotted adjustment screw 63 at that end.

45 The slotted adjustment screw has its end in engagement with one end of a compression coil spring 64, preferably of the helical type and provided at one or both ends with a sheet metal cap 65, 66. Each spring unit 60 is suitably secured in the sash by a tight frictional drive in a bore 50 which communicates with the slot 36.

The metal cap 66 is adapted to engage the edge of the locking bar 35, and in order that the locking bar may be received in the groove 36, although the tubular member 61 extends to the edge of the sash, the tubular member 61 is provided with a pair of slots 67 in its opposite walls for slidably receiving locking bar 35.

By means of the adjustment screw 68, the tension of the springs 64 may be adjusted and equalized, and the adjustment may be made such that the locking bar 35 is resiliently urged into engagement with the locking shoulders 84, 85, but it may be retracted by a suitable actuating mechanism further to be described.

The actuating mechanism for the locking guide bar 35 includes a rearwardly extending rack bar 70, which is provided with the gear teeth 71 and an elongated slot 72 (Fig. 10). This rack bar 70 is slidably mounted in a gear housing, indicated in its entirety by the numeral 73.

The rack bar 70 is preferably located midway between the ends of the guide bar 35 and extends at right angles thereto so that any pull on the rack bar acts equally on both of the ends of the guide bar 35. The housing 73 may be located in a suitable recess 74, which is formed in the right-hand frame member of each sash, and which communicates with the slot 36.

This housing may consist of a U-shaped sheet metal member 75, which has a flat base 76 and flat upper and lower walls 77 and 78 at right angles to the base. The walls 77, 78 are carried by the attaching flanges 79 extending upwardly and downwardly and provided with the apertures 80 for receiving the wood screws 81.

A suitable sheet metal partition 82 may be seen in vertical section in Fig. 7 is of sufficient width to fit in between the upper and lower walls 77, 78 of the housing 75. This partition member 82 may consist of a flat piece of sheet metal preferably rectangular in form and provided with apertures at 83 and 84 for receiving wood screws 85 and 86, respectively.

The upper edge of the partition member 82 is bent horizontally at 87, downwardly at 88, and inwardly at 89, to form a box-like member which fills that end of the housing 75, and the flange 89 is adapted to slidably engage the upper edge of the rack bar 70. The wood screw 85 may support a roller 90, rotatably mounted on the shank of the screw, and of sufficient length to fit between the partition 82 and back wall 76 of the housing. The roller 90 has a sliding fit in slot 72 of the rack bar 70, and it serves to guide the rack bar and to prevent the rack bar from springing wholly out of its recess 36 and the housing 73 when the sash is removed from the window.

The partition 82 is also provided with an aperture to serve as a bearing for a shaft 91, which is fixedly secured or keyed to the pinion 92, the teeth of which engage the teeth 71 of rack 70. Shaft 91 has an outwardly extending square or non-circular end 93, which is provided with a threaded bore 94 for receiving a screw bolt 95.

The key 96 comprises a central metallic body of tubular shape, formed with a bore 97 for receiving the bolt 95, and with a non-circular socket 98 for receiving the square end 93 of shaft 91. The radially extending wings 99 serve for engagement with the fingers, and it will be evident that the key may be permanently attached by means of the screw bolt 95, or the bolt may be eliminated so that the key is removed at will.

The recess 74 is of sufficient depth so that the

slot 36 is located inwardly of the surface of the sash, and shaft 91 extends to a point below a cover plate 100. The cover plate 100 is of sufficient size to cover the complete housing, and has apertures 101 which register with the apertures 80 in the housing member 75.

Thus, four screws 81 may be used to secure the housing together and fasten it to the sash, in addition to the screws 85, 86, which secure the partition 82 in place.

The cover plate 100 has an aperture 102, which has its center concentric with the axis of shaft 91, and which is of sufficient size to pass the shank of the key 96.

Referring to Fig. 8, this shows a locking pin 103, which is inserted in the auxiliary apertures 104, 105, and engages in the slot 72 when the rack 70 and locking bar 35 have been wholly retracted into the housing 73. Pin 103 may thus be used to lock a bar 35 in the retracted position.

The angle iron members 106 may be utilized for preventing insertion of a knife or tool from the outside of the sash, particularly the lower sash. These angle iron members may extend the full length of the lower sash, but no farther, as they would otherwise interfere with the removal of the upper sash. Each angle iron member (Fig. 3) has one flange 107 recessed in the vertical frame member 20 or 31, and the other flange extending into the window opening in position to engage the outer face of the sash.

The flange 107 may be secured to the frame members 20 or 31 by a plurality of wood screws passing through apertures in the flange 107. The operation of the sash installation is as follows:

When the upper sash is in its uppermost position, it is locked by engagement of the locking bar with the uppermost square headed stop screws 52. The same is true of the lower sash in its lowermost position.

The lower sash may be raised to ventilation position by applying the key and turning it counterclockwise, which will retract the rack 70 and locking bar 35 against the tension of spring units 60 so as to withdraw the locking bar 35 from engagement with the stop screws 51 or 52.

When the locking bar is in this position, the window may be raised by hand to any desired position, one hand being used on the key, and the other on the handle in the window. Both the upper and lower sash are preferably provided with the centrally located handles, which are customarily used on the lower sash only.

In a similar manner the upper sash may be locked in ventilation position by engagement of its locking bar with the square headed stop screws 51.

After either sash has its locking bar moved out of the range of the two square headed screws, movement is permitted in one direction without using the key; that is, the upper sash may be moved upward or the lower sash may be moved upward, without the key. When this is done, the beveled camming surfaces 58 on the lower side of each of the grooves 40-50 of the locking bar 35 are cammed inward by the round headed screws on upward movement only.

It will be evident that either sash may be secured in any of a plurality of positions, and the location of the grooves 40-50 and the stop screws 51, 52 at frequent intervals gives a sufficient number of positions to satisfy practically any condition.

At any time either sash may be removed by

retracting the locking bar wholly into its recess in the sash and pivoting the sash inward, and it is not necessary to incur the danger of working on windows from the outside of the building. Both sides of the windows may be painted or washed from the inside of the building.

The present arrangement eliminates wholly the use of the customary window stops, and it is not necessary to provide the usual sash weights and cords, as the sashes are held in the desired position by the guiding and locking bar.

In order to close the window, the key is used to retract the bar into its recess sufficiently to clear the screw heads, and the sash is slid upward or downward, as the case may require.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A guiding and locking mechanism for a window sash, comprising a guide member having a flange adapted to be secured to a sash and a guide flange adapted to extend laterally of the sash into a slot of the window frame, said guide flange extending in the direction of sliding movement of the sash for supporting one side of the sash, and guiding and locking means for the other side of said sash, comprising a retractable guide and locking bar adapted to be slidably mounted on the other side of said sash for projection from and retraction into the edge of the sash, said locking bar having shoulders for engaging stop means to be carried by the frame, and said stop means comprising a plurality of wood screws adapted to be secured in a slot in the frame, the slot receiving said locking bar, each of said screws having a side provided with a camming surface on one side and with an abrupt shoulder on the other side, whereby the locking bar may be cammed over said stop means on movement of the sash in one direction, but will have its shoulders engaging the stop means to prevent movement in the other direction.

2. A guiding and locking mechanism for a window sash, comprising a guide member having a flange adapted to be secured to a sash and a guide flange adapted to extend laterally of the sash into a slot of the window frame, said guide flange extending in the direction of sliding movement of the sash for supporting one side of the sash, and guiding and locking means for the other side of said sash, comprising a retractable guide and locking bar adapted to be slidably mounted on the other side of said sash for projection from and retraction into the edge of the sash, said locking bar having shoulders for engaging stop means to be carried by the frame, and said stop means comprising a plurality of wood screws adapted to be secured in a slot in the frame, the slot receiving said locking bar, each of said screws having a side provided with a camming surface on one side and with an abrupt shoulder on the other side, whereby the locking bar may be cammed over said stop means on movement of the sash in one direction, but will have its shoulders engaging the stop means to prevent movement in the other direction, and resilient means engaging said locking bar adjacent each end, and adapted to be mounted in

said sash for resiliently urging the locking bar into the groove of said frame, and into engagement with said stop means.

3. A guiding and locking mechanism for a window sash, comprising a guide member having a flange adapted to be secured to a sash and a guide flange adapted to extend laterally of the sash into a slot of the window frame, said guide flange extending in the direction of sliding movement of the sash for supporting one side of the sash, and guiding and locking means for the other side of said sash, comprising a retractable guide and locking bar adapted to be slidably mounted on the other side of said sash for projection from and retraction into the edge of the sash, said locking bar having shoulders for engaging stop means to be carried by the frame, and said stop means comprising a plurality of wood screws adapted to be secured in a slot in the frame, the slot receiving said locking bar, each of said screws having a side provided with a camming surface on one side and with an abrupt shoulder on the other side, whereby the locking bar may be cammed over said stop means on movement of the sash in one direction, but will have its shoulders engaging the stop means to prevent movement in the other direction, and resilient means engaging said locking bar adjacent each end, and adapted to be mounted in said sash for resiliently urging the locking bar into the groove of said frame, and into engagement with said stop means, and rotatable means for retracting said locking bar into the sash against the pressure of said resilient means.

4. In a window sash hardware, the combination of a metallic guiding member having means for its securement to one edge of a sash, and having a guide flange adapted to slide in a longitudinally extending slot in a window frame, with a retractable guide bar adapted to be slidably mounted in a groove in the opposite side of said sash, and slidably engaged in a groove in the opposite side of the window frame, resilient means adapted to be carried by said sash and engaging said guide bar adjacent each end, and urging said guide bar out of said sash into engagement with the groove of said frame, said guide bar being provided with a plurality of slots and a plurality of stop members adapted to be located in the groove of said frame below the upper edges of the groove, whereby the guide bar may be retracted sufficiently to clear said stop members and still effect a guiding of the sash, or the guide bar may be released to engage the stop members to secure the sash in any of a plurality of adjusted positions, or the guide bar may be wholly retracted from the groove to permit the sash to be pivoted in a direction transverse to the guide bar, out of the frame.

5. In a window sash hardware, the combination of a metallic guiding member having means for its securement to one edge of a sash, and having a guide flange adapted to slide in a longitudinally extending slot in a window frame, with a retractable guide bar adapted to be slidably mounted in a groove in the opposite side of said sash, and slidably engaged in a groove in the opposite side of the window frame, resilient means adapted to be carried by said sash and engaging said guide bar adjacent each end, and urging said guide bar out of said sash into engagement with the groove of said frame, said guide bar being provided with a plurality of slots and a plurality of stop members adapted to be located in the groove of said frame below

the upper edges of the groove, whereby the guide bar may be retracted sufficiently to clear said stop members and still effect a guiding of the sash, or the guide bar may be released to engage the stop members to secure the sash in any of a plurality of adjusted positions, or the guide bar may be wholly retracted from the groove to permit the sash to be pivoted in a direction transverse to the guide bar, out of the frame, certain of said stop members being provided with abrupt shoulders on both sides to secure the sash firmly against movement from the outside.

6. In a window sash hardware, the combination of a metallic guiding member having means for its securement to one edge of a sash, and having a guide flange adapted to slide in a longitudinally extending slot in a window frame, with a retractable guide bar adapted to be slidably mounted in a groove in the opposite side of said sash, and slidably engaged in a groove in the opposite side of the window frame, resilient means adapted to be carried by said sash and engaging said guide bar adjacent each end, and urging said guide bar out of said sash into engagement with the groove of said frame, said guide bar being provided with a plurality of slots and a plurality of stop members adapted to be located in the groove of said frame below the upper edges of the groove, whereby the guide bar may be retracted sufficiently to clear said stop members and still effect a guiding of the sash, or the guide bar may be released to engage the stop members to secure the sash in any of a plurality of adjusted positions, or the guide bar may be wholly retracted from the groove to permit the sash to be pivoted in a direction transverse to the guide bar, out of the frame, predetermined of said stop members being provided with camming surfaces on one side and an abrupt shoulder on the other side, and said slots being formed with a beveled surface on one side whereby the sash may be moved in one direction, the movement of the sash causing the locking bar to be cammed inward.

7. In a window sash hardware, the combination of a combined locking and guide bar adapted to be slidably mounted in a groove in the edge of a sash, said guide bar having a plurality of stop shoulders and camming surfaces, and stop means having a stop-engaging shoulder adapted to be located in a groove in the frame of a window, said latter groove receiving said guide and locking bar, and means for controlling the movement of said guide and locking bar, whereby the bar may be wholly retracted into the sash to move the sash out of the frame, or the bar may be used for slidably supporting the sash in the frame, or the bar may be engaged with said stop means for holding the sash in any of a plurality of adjusted positions.

8. In a window sash hardware, the combination of a combined locking and guide bar adapted to be slidably mounted in a groove in the edge of a sash, said guide bar having a plurality of stop shoulders and camming surfaces, and stop means having a stop-engaging shoulder adapted to be located in a groove in the frame of a window, said latter groove receiving said guide and locking bar, and means for controlling the movement of said guide and locking bar, whereby the bar may be wholly retracted into the sash to move the sash out of the frame, or the bar may be used for slidably supporting the

sash in the frame, or the bar may be engaged with said stop means for holding the sash in any of a plurality of adjusted positions, said controlling means comprising compression springs adapted to be carried by the sash and to urge the bar outward at both of its ends.

9. In a window sash hardware, the combination of a combined locking and guide bar adapted to be slidably mounted in a groove in the edge of a sash, said guide bar having a plurality of stop shoulders and camming surfaces, and stop means having a stop-engaging shoulder adapted to be located in a groove in the frame of a window, said latter groove receiving said guide and locking bar, and means for controlling the movement of said guide and locking bar, whereby the bar may be wholly retracted into the sash to move the sash out of the frame, or the bar may be used for slidably supporting the sash in the frame, or the bar may be engaged with said stop means for holding the sash in any of a plurality of adjusted positions, said controlling means comprising compression springs adapted to be carried by the sash and to urge the bar outward at both of its ends, said springs being housed in tubular members, slotted for reception of said bar.

10. In a window sash hardware, the combination of a combined locking and guide bar adapted to be slidably mounted in a groove in the edge of a sash, said guide bar having a plurality of stop shoulders and camming surfaces, and stop means having a stop-engaging shoulder adapted to be located in a groove in the frame of a window, said latter groove receiving said guide and locking bar, and means for controlling the movement of said guide and locking bar, whereby the bar may be wholly retracted into the sash to move the sash out of the frame, or the bar may be used for slidably supporting the sash in the frame, or the bar may be engaged with said stop means for holding the sash in any of a plurality of adjusted positions, said controlling means comprising compression springs adapted to be carried by the sash and to urge the bar outward at both of its ends, and adjustable threaded means for engaging said compression springs whereby the outward pressure of the bar may be equalized and adjusted.

11. In a window sash hardware, the combination of a combined locking and guide bar adapted to be slidably mounted in a groove in the edge of a sash, said guide bar having a plurality of stop shoulders and camming surfaces, and stop means having a stop-engaging shoulder adapted to be located in a groove in the frame of a window, said latter groove receiving said guide and locking bar, and means for controlling the movement of said guide and locking bar, whereby the bar may be wholly retracted into the sash to move the sash out of the frame, or the bar may be used for slidably supporting the sash in the frame, or the bar may be engaged with said stop means for holding the sash in any of a plurality of adjusted positions, said controlling means comprising compression springs adapted to be carried by the sash and to urge the bar outward at both of its ends, and stop means comprising a member extending through an elongated aperture located in a backwardly extending member carried by said bar for positively limiting the outward movement of the bar.
